(57) **CLAIM**

The ornamental design for a dock for aerial vehicles, as shown and described.

DESCRIPTION

FIG. 1 is a top isometric view of a dock for aerial vehicles.

FIG. 2 is a bottom isometric view thereof.

FIG. 3 is a rear elevation view thereof.

FIG. 4 is a front elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The dot-dash broken lines depict boundaries of the dock for aerial vehicles that form no part of the claimed design. The equal length broken lines depict portions of the dock for aerial vehicles or replicas thereof that form no part of the claimed design.

1 Claim, 6 Drawing Sheets
